UNITED STATES PATENT OFFICE.

LEWIS J. EVANS, OF KIRKWOOD, NEW YORK, ASSIGNOR OF ONE-FOURTH TO COE TYLER AND THREE-EIGHTHS TO JOHN M. DAVIDGE, OF BINGHAMTON, NEW YORK.

MAIL-BAG-DELIVERY APPARATUS FOR CARS.

No. 913,715.

Specification of Letters Patent.

Patented March 2, 1909.

Application filed December 23, 1907. Serial No. 407,797.

To all whom it may concern:

Be it known that I, LEWIS J. EVANS, citizen of the United States, residing at Kirkwood, New York, have invented certain new and useful Improvements in Mail-Bag-Delivery Apparatus for Cars, of which the following is a specification.

My invention relates to apparatus for use in the railway mail service, and particularly to means for delivering mail bags from the cars at the different post offices along the road.

In carrying out my invention I aim to provide means whereby the various conditions of the service may be met with safety to the employees, and whether the car be running in the one direction or the other, or whether the invention be used upon a single, double or four-track road delivering night or day.

One object of my invention is to provide a simple and effective mechanism which will positively eject the mail bags from the car without requiring the railway mail clerk to assume a position of danger, the apparatus being so arranged that it may be employed at either side of the car.

The invention consists in the features and combination and arrangement of parts hereinafter described and particularly pointed out in the claims.

In the accompanying drawings, Figure 1 is a side elevation of a railway mail car and the net by my improved form adapted to receive the mail bag therefrom. Fig. 2 is a cross sectional view of a car with my improvements attached thereto. Fig. 3 is a detail view showing a different way of operating the delivery mechanism from that shown in Fig. 2. Fig. 4 is a detail view of a part of a car and the post which carries the catcher in proper relation thereto and the net which is adapted to receive the mail bag from the car. Fig. 5 is a detail front view of the delivering apparatus and indicator indicating stations night or day. Fig. 6 is a plan view of the delivering apparatus. Fig. 7 is a view of a chute of large capacity adapted to take a number of mail bags. Fig. 8 is a view of a battery of delivery chutes adapted to deliver one, two or three mail bags as may be needed from the car at approximately the same time. Fig. 9 is a detail view of the indicating chart. Figs. 10 and 11 are views of a receptacle or receiver adapted to be arranged along side of the track and between

the tracks to receive the bag from either track.

In these drawings 1 represents the railway car of substantially ordinary construction. I provide in the side of the car an opening 2 through which the mail bag is delivered. Extending from the inside of the car transversely thereof is a chute or trough 3 having its end projecting through the opening in the side of the car, the said chute being of substantially cylindrical form in cross section, but having an open top to permit the mail bag to be placed therein. The chute is curved from end to end on the arc of a circle struck from the point 4 as a center and the chute is supported at this point 4 by means of arms 5, 6, extending from near the opposite ends of the chute to the point of support 4. The supporting pin at this point is supported in the up-turned sides 7 of a base plate or bracket 8, which is attached to the floor of the car. The chute is slotted longitudinally along its lower side at 9, in which slot the delivery arm or ejector 10 is adapted to move. This delivery arm or ejector is provided with a cup shaped head or member 11, adapted to receive the bottom of the mail bag when this is placed in the chute. The delivery arm 10 is under tension of a spring which is coiled about the supporting pin 4 to which the arm 10 is fixed. The arm 10 is rigidly fixed to a collar 12 and this in turn is suitably fixed to the pin or shaft 4. The coil spring at one end engages the arm 10 and at the other end it bears upon a fixed part of the structure. By drawing the arm back in the position shown in Fig. 2 it is placed under the strong tension of the spring mentioned, and for locking the arm or setting it in this position I employ a detent or catch 12' pivoted to the base at 13 to swing in a direction longitudinally of the car, the said detent having a lug or tooth 14 projecting laterally to engage a lug or projection 15 on the delivery arm 10. I prefer to make the under side of the tooth 14 slightly concave to receive the projection 15 so that the catch will be maintained securely in engagement with the lug 15.

For operating the detent so as to release the delivery arm 10 and thereby discharge the mail bag from the car I employ a rod or link 15' attached to an arm 16 extending horizontally from the detent or setting catch, the upper end of said link being connected with an arm 17 carried by a trip lever 18 piv-

oted at 19 to the car structure and having its upper end projecting as at 20 above the roof of the car. This trip lever is thus located in the path of a suitable projection at the post office station, so that as the car passes the trip lever will be operated by contact with said projection or arm at the station, thus swinging the detent lever 12' from engagement with the delivery arm 10 and allowing 10 the spring 8' to exert its force to move the delivery arm to the left and thus eject the mail bag from the chute out through the side of the car. I provide, in the path of the delivery arm, a buffer spring 21 which will return 15 the delivery arm 10 to a point within the car after it has performed its delivery action. The force of the spring 8' is sufficient to carry the delivery arm a considerable distance beyond the location of the buffer spring 21 so as 20 to discharge the mail bag with certainty.

For returning the delivery arm to the position shown in Fig. 2, I provide a handle 22 adapted to detachably engage the head 23 of the delivery arm, and when the parts are set 25 in the position of Fig. 2 this handle may be removed and placed in a suitable support, such for instance as is shown on the side of the chute in Fig. 2 at 24, where it will be readily accessible for use. For attaching the 30 delivery apparatus to the floor of the car I provide a projection 25 on the base adapted to engage an eye 26 on the floor of the car at one end, the other end of the base having an extension 27, which is held by a screw 28 35 passing therethrough and into a socket 29 in the car floor. There is one of these sockets and one of the eyes 26 at each side of the car, and in order to deliver mail through the side of the car opposite to that shown in Fig. 2, 40 the screw 28 is removed and the whole delivery apparatus is detached from the eye 26 at one side and is shifted to the opposite side of the car where it is engaged by the eye 26 and the screw 28 is then used to secure the base 45 plate to the other socket 29. In order to allow this shifting of the delivery apparatus to be performed the chute must first be withdrawn from the opening in the side of the car and this is readily done by simply swinging 50 the chute together with the arms 5 and 6 inwardly about the pivot 4.

I prefer to form the chute with a decided downward trend at or near the side of the car, whereas the inner end of the chute I 55 prefer to have only slightly inclined downwardly so that the chute, say for one-half its length from its inner end is of such form as to hold the bag substantially horizontally, while the outer end of the chute curves 60 downwardly at a sharp angle so that with a heavy bag a minimum amount of pressure or force will be necessary in order to start it on its flight, and the decided downward trend of the outer portion of the chute 65 will materially assist in the discharge action

and render it possible to deliver heavy bags with a minimum force of spring pressure.

I may, instead of operating the catch 12' from an overhead connection, employ an arm as shown at 28^X Fig. 3, pivoted at 29' 70 to the car floor. This arm has a detent 14 at its upper end and its lower end is arranged to be operated by projections along side of the track.

As shown in Fig. 1, I prefer to operate the 75 trip lever 20 by means of an arm 30 on a mail bag catcher mechanism shown generally at 31, this catcher being supported on a post 32 arranged at the station along side of the track, and its function being to hold 80 a mail bag so that it may be caught by the car as it passes the station and this catching action results from the operation against the arm 30 of a projection on the car. This projection in the present embodiment of my 85 invention consists of the trip lever 20. The parts are so related that when the members 20, and 30 contact with each other the trip lever 20 will be the first to yield, thus releasing the delivery mechanism for the discharge of the mail bag from the car and this trip lever having been operated to its limit provides enough resistance to then cause the tripping of the arm 30 of the mail bag catcher mechanism, resulting in the discharge of the mail bag from the catcher mechanism 31 and its delivery to the car. The car is equipped with a chute as indicated at A, Fig. 1, by which the mail bag, 90 from the catcher 31, is caught and directed 100 from the top of the car into the interior thereof.

I may employ, as shown in Fig. 7, a chute of sufficient capacity for three mail bags at once, or as shown in Fig. 8 I may employ a 105 battery of chutes to be operated at substantially the same time. Of course more or less of these battery chutes may be employed, those that are not employed for discharging the mail bag simply remaining inactive, in 110 other words their delivery arms not being set for action.

For receiving the mail bag at the station I employ a net 33 which is hung from a supporting frame which may consist of a spring arm 34 journaled on the post 32. This swinging arm is used when the net is employed on a single or double track road. For a four track road the net is provided with two compartments divided by the vertical partition 35 having two mouths at 36, 37, so that a mail bag can be received from either side. When this double form of net is employed it is hung from a rigid bar 38 as shown in Fig. 1. Springs 39 attached to the net serve to hold the same in position. I show in Fig. 1 the position assumed by the end of the net when a mail bag is discharged into the same.

In order to indicate the approach to a 130

station I employ an indicator 39' set up along side of the delivery mechanism as shown in Fig. 5, this consisting of a suitable chart having the names of the stations thereon and a pointer 40 which is operated through a shaft 41 and a suitable train of mechanism extending to the car axle 42 substantially as shown, so that the mail clerk by glancing at the chart can tell at what point along the route the car then is, and he can determine how much time he has to place the bag in the chute for the next delivery. I provide a loop at 41' to act as a stop against which the delivery arm bears when fully retracted and by which the machine may be drawn when reversing same to other side of the mail car.

It will be observed that with my improvement the operations of taking the bag or catching it and delivering into the car as well as the operation of discharging or delivering the bag from the car are performed through means located above the car and in a position which is best for the safety of the mail clerk or the crew on the train.

The net of double form as employed by me can be used between the tracks of either a double or a four-track road and is representative of any suitable form of receiving means to be located between the tracks and receive a bag from either side. The delivery arm may be set by power gearing particularly when it is intended to deliver a number of bags.

35 Instead of the net I may employ a receptacle composed of rigid material as shown in Figs. 10, 11, this comprises a partly cylindrical trough or receiver 42' which is rigidly supported in a casing 43. Extending longitudinally of this trough is a partition pivoted at its upper end so as to swing in either direction. The trough is adapted to receive a mail bag from either side and can thus be used on a double or four-track road as well as 40 upon a single track. The pivoted partition on the impact of the bag swings to one side and its lower edge strikes against the side of the trough and it thus forms a continuation of this side of the trough and directs the bag into the trough whereupon the bag is directed by means of the curved end 44 of the trough into the receptacle 45 beneath the trough and access to this receptacle can be had only through a door, the lock of which is controlled by the postmaster. Each end of the trough has the curved shield or directing portion so that the apparatus will operate with a train running in either direction. No matter which side the bag is thrown from into 45 the trough it will strike the hinged partition, which by abutting against the opposite side of the trough will direct the bag into the same.

I claim as my invention:—

65 1. A mail bag delivery apparatus comprising

ing a chute arranged transversely of the car of curved form, a delivery arm pivotally supported below the chute and movable along the chute, means for applying power to the delivery arm, means for setting the arm 70 ready for action and means for releasing the said arm for the discharge of the mail bag, said means being actuated when the cars arrive at the delivery station, substantially as described.

75

2. In combination in a mail bag delivery apparatus, a curved chute extending transversely of the car of substantially cylindrical form in cross section and having an open top to receive the bag, a delivery arm pivoted at 80 a point below the chute, means for operating and controlling said arm, said chute being slotted for the movement of the arm therein, substantially as described.

3. In combination with the delivery chute 85 having an open top to receive the bag, a pivoted delivery arm movable along the chute and having a cup shaped member to receive the end of the bag and means for controlling and actuating the delivery arm, substantially as described.

4. In combination, a chute to receive the mail bag having its outer end directed laterally of the car and downwardly, and a discharge arm pivotally supported and movable along the chute with means for operating and controlling the discharge arm, substantially as described.

5. In combination in an apparatus of the class described, a chute within the car having its end directed to the opening in the car, said chute being of curved form with a steep incline at its outer end and its inner end curved slightly downward, and an ejector moving in the said chute with means for controlling and operating the same, substantially as described.

6. In combination with a car, a delivery chute extending to an opening in the car and with its end in said opening, an ejector for 110 discharging the mail bag working in the chute, and pivoted supporting means for the chute, said means swinging in a vertical plane to withdraw the chute from said opening, substantially as described.

115

7. In combination with a chute having its end extending into an opening in the car, said chute being curved on substantially the arc of a circle and a support for the said chute pivoted substantially at the center of 120 the said arc and means for ejecting the mail bag from the chute, substantially as described.

8. In combination with a chute, a pivoted support therefor, an arm arranged to turn 125 about the said pivot, a spring for pressing the said arm, and means for holding and releasing the arm, substantially as described.

9. In combination with a chute and the pivoted arm operating transversely of the 130

car, a detent engaging a projection on the arm, said detent being pivoted to swing in a direction longitudinally of the car, substantially as described.

- 5 10. In combination with the delivery means within the car, means at the top of the car for controlling the said delivery means and a mail bag holding device to actuate the said controlling means, said controlling means reacting on the mail bag holding device to cause the same to actuate to permit the car to catch the mail bag therefrom, substantially as described.
- 10

11. In combination with the chute, a
15 spring pressed delivery arm and a spring
buffer against which the arm impinges, said
buffer tending to return the arm, substan-
tially as described.

12. In combination in an apparatus of the
20 class described, a receptacle for the bag
having its interior divided into two com-
partments to receive a mail bag from either
side, and means for supporting said recepta-
cle whereby it may be employed alongside
25 or between the tracks, substantially as de-
scribed.

13. In combination with the delivery apparatus on the car, the catcher apparatus, a trip for the delivery apparatus, a trip for 30 the catcher apparatus, said trips being operated by contact with each other, substantially as described.

14. In apparatus of the class described, a receiving trough having a hinged partition

extending longitudinally thereof and adapted 35 to receive the impact of the bag from either side and to direct the bag into the trough, substantially as described.

15. In combination with a trough, the receptacle beneath the same and means for 40 directing the bag from the trough into the receptacle, substantially as described.

16. In combination with a trough, the receptacle beneath the same and means for directing the bag from the trough into the receptacle, said means consisting of the curved shield at the end of the trough, substantially as described.

17. In combination in apparatus of the class described, a trough to receive the mail bag from either side, a receptacle beneath the trough and a curved shield at each end of the trough to direct the mail into the receptacle no matter in which direction the train is running, substantially as described. 50 55

18. In combination with the chute and the delivery arm, a detent engaging a part of the said delivery arm, said detent having a concave face whereby it will be maintained in position until sufficient force is applied, substantially as described.

In testimony whereof, I affix my signature
in presence of two witnesses.

LEWIS J. EVANS.
